UNITED STATES PATENT OFFICE.

DANIEL WELLS, OF PHILADELPHIA, PENNSYLVANIA.

BURGLAR-ALARM.

Specification of Letters Patent No. 12,177, dated January 2, 1855.

To all whom it may concern:

Be it known that I, DANIEL WELLS, of the city of Philadelphia and State of Pennsylvania, have invented a new and Improved 5 Mode of Giving Motion to an Alarm from the Opening of a Door; and I do hereby declare that the following is a full, clear, and exact description of the same; reference being had to the accompanying drawing and 10 to the letters of reference marked thereon.

The nature of my invention consists in attaching to the outside edge of any ordinary door a radiating arm having a projection which on the door being closed catches into 15 a notch on a bolt in the jamb, and on reopening the door gives the said bolt a perpendicular movement communicated by rods or wires to a trigger which releases a spring bolt and thereby sets in motion an alarm 20 situated in any convenient position.

In order to enable others skilled in the art to make and use my invention I will now proceed to describe its construction and operation.

25 In reference to the drawing, Figure 1 is a view of my improved apparatus attached to an ordinary door and jamb with the former partially closed. Fig. 2 is a view of the same with the door in the act of being 30 opened. Fig. 3 is a view of the spring bolt and trigger showing the manner in which it is connected to the latch on the jamb.

The same letters of reference allude to similar parts throughout the several views.

35 B is the door to the outside edge of which is secured the metallic plate D. At the back of this plate is a radiating arm d the lower end of which works on a pin in the plate, the upper end being provided with a projection e standing out at right angles from the arm and protruding through a slotted opening in the plate D. A spring f one end of which is secured to the top of the plate and the other end bearing against the lower end 40 of the arm d serves to maintain the latter in a perpendicular position when not otherwise moved by the closing of the door.

A is the door jamb which has also secured to it a metal plate C. At the back of this 50 plate is the latch a which is attached to the plate by means of the arm b the latter working on a pin in the plate and another pin in the latch a so that the latter can have a perpendicular movement only. Near the top of 55 the latch a is cut a recess x having a notch on

the top of such a form and in such a position as to receive the projection e on the radial arm d when the door is closed. The latch a has likewise a projection which when the apparatus is in action rests on the point of the cam c. This cam is allowed to turn loosely on the plate C by means of a key inserted into the square central hole so that when the point of the cam is turned in a horizontal position as shown in dotted lines the latch a may drop down and be free from contact with the projection e on the radial arm d when the door is opened or closed. To the lower end of the latch a is secured the wire or cord k which passing through the floor E is connected to the end of the trigger n. This trigger works on a pin in the plate G which is attached to the floor E by any convenient means. The short arm of the trigger lever n is notched so as to receive the square end of the bolt o which slides in pieces on the plate G. Round this bolt is coiled a spiral spring p one end of the wire composing which is attached to the plate G the other to the bolt in such a manner that when the square head is released from contact with the trigger the bolt will be suddenly projected in the direction of the arrow.

A spring s bearing against the end of the trigger n serves to keep the notch in contact with the bolt o when not released by the wire k. To the end of the bolt is secured a wire (not shown in drawing) communicating with an alarm situated in any convenient position. A bell crank lever m having its fulcrum on the plate G is so arranged in connection with the wire l that when the latter is pulled upward the bolt may be forced back to its original position after being discharged as hereinafter described.

Now supposing the apparatus to be in the position shown in Fig. 1 with the latch a supported on the point of the cam c and the radial arm d in a perpendicular position. On moving the door B toward the jamb A the projection e on the radial arm d will come in contact with that portion of the latch a above the recess x. On further moving the door in the direction of the jamb the radial arm d will be inclined downward in the direction of the slot h in the plate C as shown in dotted lines. When the door is entirely closed the projection e on the arm d will have dropped into the recess x of the 110

latch *a* one corner of the projection *e* catching into a small notch in the upper part of the recess.

The apparatus is now in suitable order for giving an alarm on the reopening of the door. When this takes place the arm *d* being in an inclined position and its projection *e* continuing to retain its place in the recess *x* it will be evident that the arm *d* will in its tendency to resume a perpendicular position elevate the latch *a* and with it the wire *k* as shown in Fig. 2. This movement raises one end of the trigger lever *n* and lowering the other releases the bolt *o* which through the elasticity of the spiral spring is projected suddenly in the direction of the arrow and gives the required movement to the alarm.

When it is necessary to restore the spring bolt *o* to its former position the wire *l* is raised and with it the long arm of the bell crank lever *m* pressing the other arm against the end of the projected bolt *o* and forcing it back until the square head comes again in contact with the notched end of the trigger *n*.

The alarm may be so arranged in connection with the spring bolt *o* that it shall continue to ring until the wire is raised and the bolt *o* restored to the position shown in drawing.

As it may be frequently required to render the whole apparatus inoperative during the day I effect this by turning the cam *c* in a horizontal position which allows the latch *a* to drop and to be free from contact with the projection on the radial arm *d*, thus allowing the door to be opened or closed like any ordinary door without giving an alarm.

It may be remarked that the motion obtained from the opening of the door might be communicated direct from the wire *k* to the alarm without the intervention of the spring bolt and trigger, this however would require a considerable increase of movement from the latch *a* consequently rendering the opening of the door somewhat difficult.

With the use of the apparatus shown in the drawing the peculiar radial movement of the arm *d* in connection with the latch *a*, together with the fact of but a slight motion being required to discharge the trigger combine to render the opening of any door to which they may be attached easy, and the action of the whole almost imperceptible.

In the accompanying drawing no alarm is shown, it will be easily understood however, that any of the numerous well known alarms may be easily connected by means of wires and other suitable connections to the end of the spring bolt *o*.

I am well aware that the giving of alarms from the opening of doors is old and well known. I do not therefore wish to claim that exclusively; but

What I claim as my invention and desire to secure by Letters Patent is—

The radial arm *d* with its projection *e* and the latch *a* with its notched recess *x* for effecting the disengagement of the spring bolt on the movement of a door or its equivalent in the manner described and for the purpose specified.

DANIEL WELLS.
